APPARATUS FOR CONTROL OF HIGHWAY
CROSSING SIGNALSEaston E. Parrill, Swissvale, Pa., assignor to The
Union Switch & Signal Company, Swissvale,
Pa., a corporation of Pennsylvania

Application August 18, 1942, Serial No. 455,171

4 Claims. (Cl. 246—130)

My invention relates to apparatus for control of highway crossing signals, and more particularly to such apparatus using alternating current track circuits.

When alternating current track circuits are used to control a highway crossing signal for a railway over which traffic moves in either direction, no warning operation of the signal may result if a loss of the alternating current occurs and power is restored while a train occupies an approach track section.

Accordingly, a feature of my invention is the provision of novel and improved apparatus for the control of highway crossing signals when alternating current track circuits are used.

Other features, objects and advantages of my invention will appear as the specification progresses.

I shall describe one form of apparatus embodying my invention, and shall then point out the novel features thereof in claims.

The accompanying drawing is a diagrammatic view showing one form of highway crossing signal control apparatus embodying my invention.

In the drawing the reference characters $1a$ and $1b$ designate the track rails of a stretch of railway over which traffic moves in either direction, and which stretch is intersected by a highway H , a highway crossing signal S being located at the intersection. The rails $1a$ and $1b$ are formed by the usual insulated rail joints with two track sections $1T$ and $2T$ which have their junction adjacent the intersection and extend in opposite directions therefrom, track section $1T$ serving as an approach section for westbound traffic and section $2T$ serving as an approach section for eastbound traffic. Each track section $1T$ and $2T$ is provided with an alternating current track circuit which includes a track transformer connected across the rails at one end of the section and a track relay connected across the rails at the other end of the section, the track transformer and relay being identified by the reference characters T and R , respectively, with a prefix corresponding to the section. These track transformers are supplied with alternating current from a suitable source, and as here disclosed they are supplied with current from a generator G connected to a transmission line comprising line wires $L1$ and $L2$. Primary winding 5 of track transformer $1TT$ is connected across the line wires $L1$ and $L2$ and a secondary winding 6 of this transformer is connected across the rails of section $1T$ through a limiting resistor 7 to supply power to the track circuit

of section $1T$. Similarly, primary winding 8 of track transformer $2TT$ is connected across the line wires, and a secondary winding 9 of this transformer is connected across the rails of section $2T$ through a limiting resistor 10 to supply power to the track circuit for section $2T$.

A power-off relay POR is provided and the winding of relay POR is connected to the line wires $L1$ and $L2$ through a line transformer LT . Consequently relay POR is energized and picked up as long as alternating current is present in the transmission line, but is deenergized and released when an interruption of the supply of alternating current occurs.

15 The track relays $1TR$ and $2TR$, together with the power-off relay POR govern a directional means to provide a directional control for signal S . As here shown, the directional means is an interlocking relay IR whose magnets EXR and WXR are associated with track sections $1T$ and $2T$, respectively. Interlocking relay IR is preferably of the direct current type having flagman contacts, flagman contacts 16 and 19 being operated by the armatures of magnets EXR and WXR , respectively. Each flagman contact 16 and 19 is closed when the respective magnet armature is picked up and remains closed when the respective armature is locked at the intermediate position of the relay, but is opened when the associated armature is the first one of the two to be released. Each magnet EXR and WXR is energized by two alternative circuits, one of which serves as a pick-up circuit, and the other one of which serves as a stick circuit. The energizing circuits for the magnets of the interlocking relays, as well as the operating circuits for signal S , to be referred to later, are supplied with energy from an auxiliary source such as a battery AB . A first energizing or pick-up circuit for magnet EXR is formed from the top terminal of battery AB through front contact 11 of power-off relay POR , front contact 12 of track relay $1TR$, winding of magnet EXR and wire 13 to the lower terminal of battery AB . A second energizing or stick circuit for magnet EXR can be traced from the top terminal of battery AB through back contact 14 of relay POR , back contact 15 of magnet WXR , flagman contact 16 of magnet EXR , winding of magnet EXR , and wire 13 to the lower terminal of battery AB . Similarly, a first energizing circuit for the magnet WXR includes top terminal of battery AB , front contact 11 of relay POR , front contact 17 of track relay $2TR$, winding of magnet WXR , wire 13 and the lower terminal of battery AB ; and a second energizing

circuit for this magnet includes top terminal of battery AB, back contact 14 of relay POR, back contact 18 of magnet EXR, flagman contact 19 of magnet WXR, winding of magnet WXR, wire 13 and lower terminal of battery AB. Thus each magnet EXR and WXR is energized through its associated first energizing circuit when the alternating current is present and each track section is unoccupied, and each magnet may be energized as will be pointed out presently through its second circuit when there is a loss of alternating current.

Each magnet EXR and WXR is preferably provided with slow to release characteristics.

The highway crossing signal S may be of any desired form, such as, for example, a gate, a barrier, a flashing light, an audible signal or a combination of these devices, and it is shown as an audible signal in the form of an electric bell. The signal S is operated by energy from auxiliary source AB, the operating circuit of signal S having three alternative paths, one of which includes back contact 20 of magnet EXR, a second one of which includes back contact 21 of magnet WXR, and a third one of which includes back contact 22 of power-off relay POR.

Normally, that is, when alternating current is present and the track sections 1T and 2T are unoccupied, the power-off relay POR and the two track relays 1TR and 2TR are picked up causing the interlocking relay to be energized and signal S to be silent. If an eastbound train approaches the intersection to shunt track relay 2TR opening front contact 17, the magnet WXR of the interlocking relay is deenergized and its armature is released to its full down position where it closes the operating circuit for bell S at back contact 21 so that signal S is sounded to provide a warning indication of the approach of this train. The interlocking mechanism of the relay IR is actuated by the release of the armature of magnet WXR so that when the train enters section 1T to shunt track relay 1TR and deenergize magnet EXR, the armature of magnet EXR is locked at its intermediate position in the usual manner for such a relay. Consequently, when this train vacates the track section 2T and track relay 2TR is picked up causing magnet WXR to be reenergized, the warning operation of signal S ceases and the signal remains silent as this train recedes from the intersection through the track section 1T. If a westbound train approaches the intersection to shunt track relay 1TR opening front contact 12, magnet EXR is deenergized and its armature is released to the full down position closing the operating circuit of signal S at back contact 20 and signal S sounds its warning indication of the approach of this westbound train. The interlocking feature of the relay is actuated by the release of the armature of magnet EXR so that when magnet WXR is deenergized in response to this westbound train entering section 2T, the armature of magnet WXR is locked at its intermediate position and signal S is silent as the westbound train recedes from the intersection through section 1T. The above is the normal operation of the apparatus as long as the alternating current is present.

If a loss of alternating current on the transmission line occurs, the power-off relay and track relays are all deenergized. The loss of power on the transmission line may be, and very often is, a gradual falling away of the voltage, with the result that the relays POR, 1TR and 2TR are not deenergized simultaneously. If relay POR is re-

leased first to open front contact 11, the two magnets of the interlocking relay are deenergized simultaneously, and the two magnet armatures should drop simultaneously each falling to the full down position. However, the armatures of the magnets may not release simultaneously, and if one magnet armature falls first, the other magnet armature will be locked at the intermediate position. If the power-off relay is not used to control the interlocking relay, or if either one of the track relays is released ahead of the power-off relay, and also ahead of the other track relay, the magnet of the interlocking relay associated with the first released track relay releases its armature first, and the armature of the other magnet is locked at its intermediate position. That is to say, a loss of power may, and very frequently does, result in the interlocking relay being conditioned at a position corresponding to a directional selection. In any event, the loss of power is followed by operation of signal S, the operating circuit of signal S being completed at back contact 22 of relay POR, and also at either back contact 20 or 21 of the interlocking relay.

Assuming for illustration that there is a loss of alternating current, and magnet EXR of relay IR is deenergized ahead of magnet WXR so that the armature of magnet WXR is locked at the intermediate position, the magnet WXR is reenergized over its second circuit including back contact 14 of relay POR, back contact 18 of magnet EXR and its own flagman contact 19. Consequently the armature of magnet WXR is picked up off the interlocking mechanism of the relay. If now an eastbound train approaches the intersection and while the train occupies a section 2T, the alternating current is restored, the restoration of power will reenergize relay POR and reapply power to the track circuits. Track relay 1TR is energized, but track relay 2TR remains released due to the presence of the train in section 2T. With relay POR and track relay 1TR picked up, the magnet EXR is energized through its first circuit, and with both relay POR and magnet EXR energized, the operating circuit for signal S is open. Magnet WXR which was energized over its second or stick circuit now is deenergized because its first circuit is open at front contact 11 of track relay 2TR, and its stick circuit is open at two points, back contact 14 of relay POR and back contact 18 of magnet EXR. Because magnet WXR had been previously energized and its armature raised off the interlocking mechanism, its armature is now free to fall to the full down position, closing the operating circuit for signal S at back contact 21 to warn highway users of the approach of this eastbound train. Interlocking relay IR being now conditioned to agree with normal operation for an eastbound train, the apparatus functions in the usual manner as this eastbound train passes over the intersection and recedes through the track section 1T.

In the event a westbound train approaches the intersection subsequent to the loss of power and the conditioning of the interlocking relay with magnet EXR released and magnet WXR energized over its stick circuit, and power is restored while this westbound train occupies section 1T the power-off relay POR and track relay 2TR are reenergized. Magnet WXR which had previously been energized through its stick circuit is now energized through its first or pick-up circuit including front contact 11 of relay POR and front contact 17 of track relay 2TR. Magnet EXR, which was the first to be released when a

loss of power occurred, remains deenergized subsequent to the restoring of power due to the presence of the train in section 1T, and consequently signal S continues to be operated to provide its warning operation. Interlocking relay IR being now conditioned at the position corresponding to normal operation for a westbound train, the apparatus functions in the usual manner as this westbound train recedes from the intersection through track section 2T.

It is to be pointed out that if the control of the interlocking relay by relay POR is not provided, and if the second circuit for magnet WXR is not provided and the interlocking relay is controlled alone by the track relays or by the track circuits direct, as has been the custom heretofore, and magnet EXR is the first to be deenergized subsequent to the loss of alternating current, the armature of magnet WXR would remain locked at the intermediate position subsequent to the loss of alternating current. If then power is restored while the eastbound train occupies section 2T, the armature of magnet WXR would have been held at the intermediate position and the signal S would have failed to provide its warning indication after relay POR and magnet EXR became deenergized due to the restoration of power. Further, with the armature of magnet WXR locked at its intermediate position, the armature of magnet EXR would be free to fall to its full down position, closing back contact 20 and causing operation of signal S when the eastbound train entered section 1T and this operation of the signal would be continued while this train receded from the intersection through section 1T.

In the event magnet WXR is the first to be deenergized subsequent to a loss of power, and the armature of magnet EXR is locked at the intermediate position, magnet EXR is reenergized over its second or stick circuit including back contact 14 of relay POR, back contact 15 of magnet WXR and flagman contact 16 of magnet EXR, with the result the armature of magnet EXR is picked up off the interlocking mechanism of the relay. If now a westbound train approaches the intersection, and while it occupies the section 1T the alternating current is restored, the restoration of power reenergizes relay POR and track relay 2TR so that magnet WXR is reenergized. With relay POR and magnet WXR picked up, magnet EXR is deenergized and its armature releases to its full down position to bring about the warning operation of the signal S. Interlocking relay IR being now positioned to correspond to normal operation for westbound traffic, the apparatus functions in the usual manner as this westbound train proceeds over the intersection and recedes through the section 2T. If the second or stick circuit for magnet EXR is not provided and the magnet is controlled by the track relay alone, then its armature would have been locked in the intermediate position subsequent to the loss of power, with the result that if power is restored while the westbound train occupies the approach section 1T, no warning operation of signal S would be effected.

It is to be seen, therefore, that I have provided novel and improved control apparatus for highway crossing signals wherewith a failure of operation of the signal due to a loss of power to alternating current track circuits is avoided.

Although I have herein shown and described but one form of apparatus for control of highway crossing signals embodying my invention, it is understood that various changes and modifica-

tions may be made therein within the scope of the appended claims without departing from the spirit and scope of my invention.

Having thus described my invention, what I claim is:

1. In combination with a highway crossing signal located at an intersection of a highway and a railway track, two track sections formed in said track to extend in opposite directions from the intersection, a track circuit including a track relay and a track transformer for each of said sections, a source of alternating current connected to said track transformers to supply power to the track circuits, a power-off relay connected to said source and normally energized thereby, an interlocking relay having two magnets one associated with each track section and each magnet provided with a flagman contact, a pick-up circuit for each magnet and each pick-up circuit including a front contact of the track relay of the section associated with the respective magnet, a stick circuit for each magnet and each stick circuit including a back contact of the power-off relay and the flagman contact of the respective magnet, and circuit means controlled by said interlocking relay to operate said signal.
2. In combination with a highway crossing signal located at an intersection of a highway and a railway track, two track sections formed in said track to extend in opposite directions from the intersection, a track circuit including a track relay and a track transformer for each of said sections, a source of alternating current connected to said track transformers to supply power to the track circuits, a power-off relay connected to said source and normally energized thereby, an interlocking relay having two magnets each of which is provided with a flagman contact, a first energizing circuit for each of said magnets, the first circuit for a first one of the magnets including a front contact of said power-off relay and a front contact of a first one of said track relays and the first circuit for a second one of the magnets including a front contact of said power-off relay and a front contact of a second one of said track relays, a second energizing circuit for each of said magnets, the second circuit for said first one of the magnets including a back contact of the power-off relay and its own flagman contact and the second circuit for said second one of the magnets including a back contact of the power-off relay and its own flagman contact, and circuit means controlled by said interlocking relay to operate said signal.
3. In combination with a highway crossing signal located at an intersection of a highway and a railway track, two track sections formed in said track to extend in opposite directions from the intersection, a track circuit including a track relay and a track transformer for each of said sections, a source of alternating current connected to said track transformers to supply power to the track circuits, a power-off relay connected to said source and normally energized thereby, an interlocking relay having two magnets one associated with each track section and each magnet provided with a flagman contact, a first energizing circuit for each of said magnets and each of said first circuits including a front contact of the power-off relay and a front contact of the track relay of the section associated with the respective magnet; a second energizing circuit for each of said magnets and each of said second circuits including a back contact of the power-off relay and a front contact of the track relay of the section associated with the respective magnet.

power-off relay, the flagman contact of the respective magnet and a back contact of the other magnet; and circuit means including contacts of the interlocking relay to operate said signal.

4. In combination with a highway crossing signal located at an intersection of a highway and a railway track, two track sections formed in said track to extend in opposite directions from the intersection, a track circuit including a track relay and a track transformer for each of said sections, a source of alternating current connected to said track transformers to supply power to the track circuits, a power-off relay connected to said source and normally energized thereby, an interlocking relay having two magnets one associated with each track section and each magnet

provided with a flagman contact, an auxiliary source of power, a first energizing circuit for each of said magnets and each said first circuits including said auxiliary power source in series with a front contact of the power-off relay and a front contact of the track relay of the section associated with the respective magnet; a second energizing circuit for each of said magnets and each of said second circuits including said auxiliary power source in series with a back contact of the power-off relay, the flagman contact of the respective magnet and a back contact of the other magnet; and circuit means including contacts of said interlocking relay to operate said signal.

EASTON E. PARRILL.
